(57) **CLAIM**

The ornamental design for a golf putter head, as shown.

DESCRIPTION

FIG. 1 is a front perspective of a golf putter head showing my new design;

FIG. 2 is a rear perspective view thereof;

FIG. 3 is a toe or left side perspective view thereof;

FIG. 4 is a heel or right side perspective view thereof;

FIG. 5 is a top perspective view thereof; and,

FIG. 6 is a bottom perspective view thereof.

The broken line showing of a golf club shaft is for illustrative purposes only and forms no part of the claimed design.
